205,490

VEHICLE

Edward D. Bell, 5830 Denny Ave.,
Los Angeles County, Calif.

Filed Oct. 22, 1965, Ser. No. 87,747

Term of patent 14 years

(Cl. D90—8)

The dominant features of the design reside in the portions shown in full lines.

I claim:

The ornamental design for a vehicle, substantially as shown and described.
